[57] **CLAIM**

The ornamental design for a partially transparent card with opaque machine-readable and signature-receiving stripes, as shown and described.

DESCRIPTION

FIG. 1 is a top plan view of a partially transparent card with opaque machine-readable and signature-receiving stripes showing my new design;

FIG. 2 is a bottom plan view thereof;

FIG. 3 is a front elevational view thereof, the rear view being identical thereto; and,

FIG. 4 is a right side elevational view thereof, the left side being identical thereto.
